UNITED STATES PATENT OFFICE.

RODNEY J. WOOD, OF DAYTON, OHIO.

FILING SYSTEM.

Application filed February 7, 1921. Serial No. 443,210.

To all whom it may concern:

Be it known that I, RODNEY J. Wood, a citizen of the United States, residing at Dayton, in the county of Montgomery and 5 State of Ohio, have invented certain new and useful Improvements in Filing Systems, of which the following is a specification.

My invention relates to card index filing systems wherein data cards or sheets are 10 arranged in predetermined groups classified alphabetically, numerically or according to other arbitrary distinctions.

The object of the invention is to simplify such systems whereby they will not only be 15 inexpensive, but will be more efficient in use, compact, permitting a great number of data sheets or cards to be arranged in minimum space, yet readily accessible to enable the selection of a desired card or sheet with 20 minimum movement.

A further but none the less important object of the invention is to afford a visible file system, wherein an entire group or subdivision of the cards or data sheets may be 25 simultaneously visible to facilitate the rapidity of selection of a desired card.

A further object of the invention is to provide such a system wherein the cards are readily accessible and capable of being easily 30 and quickly removed and replaced for the purpose of making entries thereon.

A further object of the invention is to provide an improved form of data sheet or card holder or support, by which the cards 35 or sheets may be detachably supported in overlapping relation to simultaneously expose guide or reference entries on the overlapping portion of the sheet or card.

With the above primary and other incidental objects in view as will more fully appear in the specification, the invention 40 consists of the features of construction, the parts and combinations thereof, and the mode of operation or their equivalents as 45 hereinafter described and set forth in the claims.

Referring to the drawings, Fig. 1 is a perspective view of a portion of a card file embodying the present invention. Fig. 2 is 50 a perspective view of one of the holders or supports for a group of overlapping data or reference sheets. Fig. 3 is a side elevation of a holder or support showing a number of sheets or cards positioned thereon. Fig. 4 is

a detail view illustrating the adaption of 55 the invention to an alphabetical or name index.

Like parts are indicated by similar characters of reference throughout the several 60 views.

The present invention is applicable to card index filing systems for various purposes, such as card index records of customers, agents, subscribers or other lists of names, which may be arranged alphabetically or divided into groups according to occupation, residence, location character, type, or other classification, or it may be employed for stock records, wherein records of different material are to be grouped 70 according to sizes, quantities or purposes. For purpose of illustration, the card index filing system forming the subject matter hereof has been illustrated in Fig. 1 of the drawings, as a numerical file wherein the 75 cards or data sheets are grouped according to consecutive numbers. In this particular instance, for purpose of illustration, each data sheet or card holder or support is adapted to contain a group of one hundred 80 cards or sheets, arranged in subdivisions of ten sheets or cards each. The arrangement being such that the entire group of one hundred cards or sheets are simultaneously displayed.

Referring to the drawings, 1—1 represents a series of data sheet holders or supports arranged one behind the other in a continuous succession. Each of these holders or supports 1 has formed therein a 90 plurality of integral tongues 2, which are formed from the body of the holder or support by an inverted U-shaped incision. The tongue of material 2 thus formed is flexed outwardly to a position oblique or 95 inclined to the plane of the holder or support 1. These tongues are arranged in vertical spaced relation. While the tongues may extend a considerable distance across the holder or support, whereby one such 100 tongue might be employed for each subdivision of the card group, they have been shown in the drawings as arranged in pairs with the respective members of each pair aligned transversely upon a holder or support. 105 To prevent undue weakening of the holder or support, the vertical succession of tongues 2 are staggered or offset in relation one with

another, the succession of spaces or steps, however, being maintained. These tongues 2 form ledges or projections upon which are positioned the successive reference or data 5 cards or sheets 3. Each pair of aligned tongues or ledges 2 may carry one or more data or reference cards 3, according to the character, size and purpose of the file. If a 10 single card or sheet is supported upon each pair of tongues or ledges 2, the reference or data sheet being of equal size, they will present stepped or overlapping upper margins as shown in Fig. 4. In Fig. 4 there is 15 illustrated a name index in which the main support or holder 1 bears the guide designation BAK, while the several cards shown in overlapping position, carry upon their exposed margin different names beginning with the letters BAK as Baker, Baklow, 20 Bakman, Bakus, etc.

In the form of index illustrated in Fig. 1, the reference or data sheets have cut-outs or tabs of different lengths. These tabbed cards are arranged in sets wherein the tabs 25 or cut-out portions progressively overlap in a lateral direction. In this instance, ten of the cards or data sheets are shown in each of these overlapping tabbed sets. There is a set of ten of such cards supported upon 30 each pair of aligned tongues or ledges 2, whereby the different sets or sub-divisions of cards or data sheets overlap vertically, while the cards or sheets comprising each set or subdivision overlap laterally. Thus the 35 exposed tab portion of each data sheet of the group is visible, simultaneously. In this instance there being ten sets or sub-divisions of ten cards each, one hundred cards or reference sheets will be accommodated by each 40 holder or support. The holders or supports 1 being numbered in units of one hundred as for instance 2400, 2500, 2600, etc., the individual cards of the group carried by such support will bear the successive numbers beginning with the even hundred borne by the 45 support or carrier to and including 99 plus the hundred represented by the support. The group shown in Fig. 1 if complete, would embody cards or data sheets numbering 50 from 2400 to 2499 inclusive. These numerical designations appear upon the exposed portion of the overlapping tabs, and hence all of the numbers are in view simultaneously. These numbers appear in vertical and horizontal series. That is to say, they appear in tens horizontally while vertically all numbers terminating in 0, 1, 2, 3, 4, etc., will be found one above the other. It thus becomes a very easy and convenient 55 operation to locate 2455 at approximately the center of the group, being in the fifth row vertically and the sixth row horizontally, wherein every number terminates in 5. It is an easy matter to insert a small knife 60 blade or spatula, or some pointed selecting 65

implement behind the desired tab, and tip the cards or data sheet below the desired number forwardly.

The supporting ledges or tongues 2 being quite flexible will readily accommodate 70 themselves to a few or many inserted cards or sheets 3. When assembled in a file container, the tongues or ledges will fold substantially to parallelism or as nearly so as is permitted by the inserted cards or sheets. 75 The relation of the cards or sheets and the support is clearly shown in Fig. 3.

The file may be used not only as a record or directory file, but it may be utilized as a 80 file for time sheets, sales tickets, or records of other character which may be inserted behind the sheets or cards 3, whether the same be a name or directory card as shown in Fig. 4 or numerical cards as shown in Fig. 1. In the latter instance the numbers 85 may represent orders, employees, stations, or may be utilized in any manner whatsoever, and any memoranda or data pertaining thereto may be deposited behind such records or reference sheets 3. The tongues or 90 flaps 2 being flexible will accommodate such deposits of considerable size.

To stiffen and strengthen the support or carrier 1 these carriers, which are preferably 95 of card board, tag board or other tough but flexible material, have been shown provided with a marginal binding or frame 4, of sheet metal. Other methods of stiffening these supports or carriers may be utilized.

In the use of inserted data sheets, where-in a number of removable sheets are positioned behind each card, a very thin or light weight paper is employed. Due to the overlapping arrangement of the cards and sheets, the space occupied thereby is materially reduced. In practice, one hundred such sheets carried by a single support, occupy less than a half inch of space. The sheets and cards are selected by inserting behind the overlying 100 cards and sheets a thin-bladed selecting implement, knife blade or spatula.

Having thus described my invention, I claim:

1. A card index embodying a plurality of independent data sheets, a support card common to a plurality of such data sheets and a plurality of spaced tongues carried by the support card and projecting from the face thereof upon which the data sheets loosely rest in overlapping relation for to 115 and fro oscillatory movement independent of the support.

2. A card index embodying a plurality of independent data sheets arranged in groups, each group having progressively offset tab 120 portions, a support card common to a plurality of groups of such data sheets, and means for detachably engaging the groups of data sheets with the support card in overlapping relation whereby the offset tab por- 125 130

tion of each group will be exposed beyond those of the succeeding group.

3. A card index embodying a plurality of independent data sheets, a support card common to a plurality of such data sheets adapted for fore and aft oscillatory movement, and a series of flexible spaced projections upon the support card at different elevations upon which different data sheets 10 loosely rest for free oscillatory movement independent of the support card, said sheets being rearwardly adjustable substantially to parallelism with each other and with the support card upon rearward oscillation of 15 the support card, the sheets being capable of forward oscillation independent of the support card and about their points of rests upon said projections to enable the exposure of the face of a selected sheet without the 20 necessity of removing any of the sheets from the support card.

4. A card index embodying a plurality of independent data sheets, a support card common to a plurality of such data sheets, a 25 plurality of hinged tongues each formed by an incision in the body of the support card, the material forming such tongues being flexed laterally beyond the face of the support card and capable of oscillatory movement 30 to and from the plane of the support card to form rests for different data sheets, the sheets being mounted for to and fro oscillatory movement to and from the support by which any selected sheet may be exposed by tilting forwardly in unison those 35 sheets in advance of the selected sheet and for returning them to parallelism with the remaining sheets preparatory to the next selective operation.

5. A card index embodying a plurality of independent data sheets, a support card common to a plurality of such data sheets, a plurality of yielding integral tongues cut from the body of the support card and flexed 45 laterally to afford rests for the sheets, said tongues being oppositely disposed in pairs, each data sheet resting upon a pair of such tongues for free oscillatory movement.

6. A card index embodying a plurality of independent data sheets, a support card common to a plurality of such data sheets, a plurality of integral tongues formed from the body of the support card and flexed laterally to afford rests for the sheets, said 55 tongues being arranged in two series, the members of the respective series being offset in staggered relation.

7. A card index embodying a plurality of data sheets loosely arranged in groups, the sheets of each group having progressively offset tabs whereby the tab of each sheet will be exposed beyond that of the adjacent sheets, the several groups of sheets being arranged in overlapping relation whereby 60 the overlapping tabs of each group will be

exposed beyond those of the adjacent group, thereby presenting to view simultaneously the tab of each sheet of the plurality and a support common to all the groups having thereon a plurality of projections extending 70 from the face of the support and forming rests upon which the lower edges of the data sheets rest for oscillatory movement of the sheets to and from the support by which movement the normally concealed face of a 75 selected sheet may be exposed without removing same from the support.

8. A numerical index comprising a series of one hundred sheets separated into ten groups of ten sheets each, the sheets of each 80 group having progressively offset tabs whereby the tab of each sheet will be exposed beyond that of the succeeding sheet of the group, the ten groups being arranged in such relation that the ten tabs of each group are exposed beyond the tabs of the succeeding group, whereby the tabs of the entire one hundred sheets will be simultaneously exposed and a support card common to all the groups of sheets having a 85 plurality of spaced steps projecting from the support card in predetermined fixed relation on which the various groups of sheets loosely rest for free oscillatory movement.

9. A card index comprising a plurality of sheets arranged in groups, the sheets of each group being provided with overlapping tabs and the several groups of sheets being arranged with their respective tabs in overlapping relation in a direction angular to 90 the direction of the overlapping of the tabs of the sheets comprising the groups whereby all of the tabs of all of the groups will be simultaneously exposed and a support card common to all the groups of sheets 95 having stepped supports arranged in spaced relation upon which the sheets loosely rest.

10. A card index comprising a plurality of sheets arranged in groups, the sheets of each group being provided with overlapping tabs, a support common to all of the sheets of the plurality, and a series of integral tongues projecting in spaced relation from the face of the support upon which the different groups of sheets are supported 100 in stepped relation.

11. In a card index system, a support card having therein a plurality of rests for data sheets arranged at different elevations, a plurality of data leaves arranged in groups, each group of leaves having laterally overlapping tabs, each group being supported upon a different rest at a different elevation with its overlapping tabs exposed beyond those of other groups said leaves being capable of oscillatory movement to and from the support card about their points of engagement upon said rests to expose the face of any leaf without removing the leaves 115 from their rests.

12. In a card index, a support card, a plurality of supporting tongues hinged to the card at different elevations, independent data sheets supported upon the tongues at different elevations whereby portions of different sheets project beyond the margins of other sheets, said sheets and hinged supporting tongues being foldable substantially to parallelism with each other and with the supporting card, the sheets being capable of oscillatory movement to and from the supporting card, about their points of rest upon the supporting tongues to expose the face of a selected sheet without removing any of the sheets from the support. 25
13. In a card index system, a plurality of data sheets resting upon their lower edges for oscillatory movement, a support member common to all the data sheets of said plurality, and a plurality of projections extending from the face of the support at different 30
- 15 spaced levels upon which the lower edges of the different data sheets rest whereby the sheets are loosely supported at different elevations for oscillatory movement to and from the support with a top marginal portion of each sheet exposed adjacent the margins of the adjoining sheets, the sheets in advance of a selected data sheet being adapted to be tilted forwardly in unison independently of these sheets rearwardly of the selected sheet to expose to view the face of the selected sheet, such tilted sheets being returnable to substantial parallelism preparatory to the next selecting operation. 35

In testimony whereof, I have hereunto set my hand this 29th day of January, A. D. 1921.

RODNEY J. WOOD.
